OTTO WEINSTEIN, OF BOSTON, MASSACHUSETTS, ASSIGNOR TO STANDARD NECKWEAR COMPANY, A CORPORATION OF MASSACHUSETTS.

BOW NECKTIE.

Application filed March 25, 1926. Serial No. 97,401.

This invention relates to neckties, and to methods of making the same, and pertains particularly to an improvement in bow ties.

It is highly desirable that bow ties have 5 flexibility and pliability combined with adequate stiffness so that the bows maintain their shape. Heretofore, it has been customary to provide the necessary strength and stiffness by means of lining material located 10 within the wings of the bow tie and such lining as usually extended the full width of the bows filling the space from top to bottom edges.

It has likewise been customary to form the 15 bows of tubular material made up from flat rectangular pieces of decorative fabric, such as silk, having two opposite edges folded inwardly and sewed together to provide a seam along the middle of one face. A lining is inserted and the two extreme ends are 20 folded together with the seam on the inside and with the two ends abutting. Two of such units are laid face to face and are wrapt about their middle portion by a relatively narrow and smaller piece of similar 25 decorative cloth, and this piece is drawn tight and sewed at the rear, thus providing the constricted knot portion with the bows at either side. In this type of tie, twice as 30 much silk or decorative cloth is used as is visible. Such ties also have the fault of wearing at the marginal edges of the bows by reason of the stiff inner liner engaging 35 the inner surface of the bow edges, and such contact is immediate because the liner is usually the full width of the bow in order that it can be positioned for its work.

The present invention is directed toward 40 the reduction in cost of manufacture and toward the reduction or lessening of wear and is believed to be an improvement over the forms above described. One object of the invention is aimed at the elimination of wear at the wing edges and the spacing of 45 the stiffening material centrally away from the edges. Another object of the invention is to reduce the amount of silk or decorative cloth in each tie.

Briefly described, the improved tie includes in its construction, the use of an adhesive tape, relatively stiff in itself, which 50 is of less width than the bows of the tie. In the particular manner in which this tape is combined with the decorative material, it 55 provides the necessary stiffening and yet

avoids the construction which has caused the quickest wear. It eliminates the usual liner. The invention also makes possible the saving of from fifteen to twenty percent of the silk in the size of the cloth in the bows. 60

The above and other details and advantages are described and claimed in the following specification and claims and the structure is illustrated in the accompanying drawing, in which:— 65

Figure 1 is a view of the rear side of one of the strips of fabric from which the bow tie is formed, and partly broken away to illustrate the absence of the usual seam;

Figure 2 is a view of the usual bow tie 70 as made up from two such strips as illustrated in Figure 1;

Figure 3 is an enlarged vertical sectional view taken on the line 3—3 of Figure 2 looking in the direction of the arrows toward 75 the end of the loops of the bow tie; and

Figure 4 is a perspective view looking at the end of the gummed tape used in lieu of the seam and in lieu of the usual liner.

Referring in detail to the drawing, Figure 80 1 illustrates one of the tubular casings formed from a rectangular piece of cloth, two opposite sides of which have been folded toward each other with a substantial gap between the adjacent inturned edges. Figure 85 2 shows a conventional bow tie having a front piece 1 and a rear piece 2, secured together at their middle portion by a central binding strip 3 simulating the knot of a hand tied article. The strip from which the 90 parts 1 and 2 are made is shown in its partially completed form in Figure 1 as having an inner or rear face 1^a visible between the adjacent inturned edges 1^b and 1^c. The upper edge of the bow is formed by the creased 95 marginal edge of the folded portion, as at 1^d, see Figures 1 and 3. The corresponding lower edge is indicated at 1^e.

Heretofore, in sewing bow ties, it has been customary to provide a piece of cloth folded 100 into a shape substantially that of the outer dimensions of the piece shown in Figure 1 but having the distance from 1^b to 1^d and from 1^c to 1^e sufficiently great for the inturned edges to overlap enough to be sewed, 105 normally leaving a raw or rough edge at the seam. If no distinct seam is provided, the edges must overlap at least enough for the adjacent faces to be basted together. Compared to such old forms, the present arrange- 110

ment with the gap between the edges 1^b and 1^c effects a saving of from fifteen to twenty percent of cloth, depending on the width of the gap.

5 In making up the tie, after the piece of cloth is folded, as shown in Figure 1, a securing and re-inforcing strip of gummed tape is laid over the gap, bridging the same and overlapping the adjacent spaced marginal edges, as illustrated in Figure 1. Heat and pressure applied by means of a hot iron causes the strip to adhere to the decorative cloth. The tape is shown in Figure 4 as consisting of a fabric or cloth portion 4, having a layer of gum or cement 4^a. It will be noted that the edges of the tape 4 are spaced away from the marginal edges 1^b and 1^c.

Referring in detail to Figure 3, it may be understood how the article shown in Figure 1 is worked up into the bow tie. The extreme ends of the completed strip of Figure 1 are folded around until the ends abut each other and with the reinforcing strip 4 on the inside of the loop. Thus, in Figure 3, it will be observed that the broad uninterrupted face 1 is on the outside and that the opposite or inner face 1^a is next adjacent the in-turned folded edges and the gap between them. Next from the right is the layer of cement and finally, the reinforcing tape 4. This sequence of parts is duplicated at the rear side of the front folded strip. The part is now ready to be matched with a corresponding tubular casing made up in the same way and the two parts can be fastened together by the central band 3. The usual metal hook and elastic fastening strap may be attached at the rear, as desired.

From the foregoing description, it will be clear that the present invention dispenses with the usual liner, thus saving the cost of the material and the labor of cutting and inserting it. The simple expedient of heat pressing the strip 4 to the exterior of the inwardly turned folded edges saves time and labor over the usual stitching. The strip 4 possesses inherent strength and tendency to maintain its shape by reason of the substantial texture of the tape and its weave. There is no gummed surface visible on the exterior. The surface 4 is of cloth and thus the entire exterior of the completed strip shown in Figure 1 may be worked up as cloth without hindrance from stickiness due to any surface of gum or cement. It will be noted that a substantially unitary three-ply laminated structure results from the combination of the tape 4, the layer of cement 4^a and the in-turned faces of the decorative cloth to which the tape is cemented.

It will be noted further that by the present improvement, all exterior raw edges are covered. There is no chance for ravelings to come off of loose ends or cut ends because such ends are sealed by the reinforcing strip

4 throughout the length of the bows. The reinforcing strip removes the chance of stitches tearing out.

I claim:

1. In a necktie, a tubular casing comprising a main piece of cloth having two opposite edges folded inwardly and toward each other, and a combined securing and reinforcing element consisting of a gummed tape mounted on the exterior and on each adjacent opposite edge portion and extending lengthwise of the edges. 75

2. In a necktie, a tubular casing comprising a main piece of cloth having two opposite edges folded inwardly and toward each other, and a combined securing and reinforcing element consisting of a gummed tape comprising the sole piece of cloth supplemental to said main piece and mounted on the exterior and on each adjacent opposite edge portion and extending lengthwise of the edges, said tape having a surface free from gum throughout its extent on the side thereof opposite to the said inwardly folded edges of said main piece. 95

3. In a necktie, a tubular casing comprising a main piece of cloth having two opposite edges folded inwardly and toward each other and spaced apart, and a combined securing and reinforcing strip extending lengthwise of the edges and bridging the space therebetween and cemented to said edge portions on the face thereof opposite to the larger face of said main piece of cloth. 95

4. In a necktie, a tubular casing comprising a main piece of cloth having two opposite edges folded inwardly and toward each other and spaced apart, and a combined securing and reinforcing strip comprising the sole piece of cloth supplemental to said main piece and extending lengthwise of the edges and bridging the space therebetween and cemented to said edge portions on the face thereof opposite to the larger face of said main piece of cloth, said strip having a surface free from gum throughout its extent on the side thereof opposite to said inwardly folded edges of said main piece and on the exterior of the casing. 100 110

5. In a necktie, a tubular casing comprising a main piece of cloth having two opposite edges folded inwardly and toward each other, and a combined securing and reinforcing element consisting of a gummed tape comprising the sole piece of cloth adhesively secured to said casing and mounted on the exterior and on each adjacent opposite edge portion and extending lengthwise of the edges, the inner surface of said folded portions lying face to face to the inside surface 115 120 125 of the main piece of cloth.

6. In a necktie, a tubular casing comprising a main piece of cloth having two opposite edges folded inwardly and toward each other and spaced apart, and a combined se- 130

curing and reinforcing strip extending lengthwise of the edges and bridging the space therebetween and cemented to said edge portions on the face thereof opposite 5 to the larger face of said main piece of cloth, the inner surface of said folded portions lying face to face to the inside surface of the main piece of cloth.

7. In a necktie, a tubular casing comprising 10 a main piece of cloth having two opposite edges folded inwardly and toward each other and toward a median line longitudinally of the piece and with the edge of each folded portion positioned between the median line and the extreme lateral edge of the folded piece, and a combined securing and reinforcing strip extending lengthwise of the adjacent edges and bridging the space therebetween and bridging the median line 15 and cemented to the surface of the folded portions on the exterior thereof.

8. In a necktie, a tubular casing comprising 20 a main piece of cloth having two opposite edges folded inwardly and toward each other and toward a median line longitudinally of the piece and with the edge of each folded portion positioned between the median line and the extreme lateral edge of the folded piece, and a combined securing and 25

reinforcing strip comprising the sole piece 30 of cloth supplemental to said main piece and extending lengthwise of the adjacent edges and bridging the space therebetween and bridging the median line and cemented to the surface of the folded portions on the 35 exterior thereof, said strip having a surface free from gum throughout its extent on the exterior of the casing.

9. In a necktie, a tubular casing comprising 40 a main piece of cloth having two opposite edges folded inwardly and toward each other and toward a median line longitudinally of the piece and with the edge of each folded portion positioned between the median line and the extreme lateral edge of 45 the folded piece, and a combined securing and reinforcing strip comprising the sole piece of cloth supplemental to said main piece and extending lengthwise of the adjacent edges and bridging the space there- 50 between and bridging the median line and said strip being cemented to the surface of the folded portions on the exterior thereof, the inner surface of said folded portions lying face to face to the inside surface of 55 the main piece.

In testimony whereof I affix my signature.
OTTO WEINSTEIN.
